(57) CLAIM

The ornamental design for a combined fan with light fixture as shown and described.

DESCRIPTION

FIG. 1 is a perspective view of a combined fan with light fixture;

FIG. 2 is a front view of a combined fan with light fixture; FIG. 3 is a rear view of a combined fan with light fixture; FIG. 4 is a left side view of a combined fan with light fixture; FIG. 5 is a right side view of a combined fan with light fixture;

FIG. 6 is a top view of a combined fan with light fixture; FIG. 7 is a bottom view of a combined fan with light fixture; and,

FIG. 8 is another perspective view of a combined fan with light fixture.

The broken lines show portions of the combined fan with light fixture that form no part of the claimed design.

1 Claim, 8 Drawing Sheets
